UNITED STATES PATENT OFFICE.

CLAUDE A. LEWIS, OF HOUSTON, TEXAS, ASSIGNOR TO AMERICAN WINDOW COMPANY,
OF HOUSTON, TEXAS, A CORPORATION OF DELAWARE.

MOUNTING FOR WINDOW SASHES.

Application filed December 14, 1926. Serial No. 154,665.

My invention relates to windows for dwellings, offices and similar buildings, and pertains more particularly to the means of mounting the window sash for movement in the frame or casing.

The invention has particular application to the lower sash of the window and has for its object the allowing of the window sash to slide vertically, and also to be swung forwardly into the room so as to allow access to the outer side of the sash for cleaning.

It is my aim to mount the sash upon opposite riders which are slidable in the casing and to attach the sash to said riders so that the upper end of said sash can be readily disengaged from the riders for swinging movement on said riders, and also firmly held in the riders so that the sash will not accidentally become detached therefrom in use.

I also provide means to limit the upward movement of the rider which will cushion the stopping of the rider and also prevent noise in operation.

Referring to the drawing herewith, Fig. 1 is a vertical section through a window frame in such manner as to remove one side thereof along the line between the sash and rider. Fig. 2 is a top plan view of one of the riders. Fig. 3 is a side elevation of one of said riders. Fig. 4 is a rear or outer view of said rider. Figs. 5 and 6 are side and end views respectively of the pivot pins employed.

The window frame with which my invention is shown is of wood and of the conventional form, although it is to be understood that the invention may be adapted to any type of frame either of wood or metal. The upper sash 1 is not slidable, but has, on each side at the lower end thereof, a hinge plate 2 secured to the sash and having a forward arm 3 thereon, the forward end of which is curved downwardly at 4 on the arc of a circle. Its upper forward end is hooked to provide an upwardly diverging recess 5 to receive the upper pin 6 of the lower sash. Said sash may be thus swung inwardly at the upper end. On the outer end of plate

2 is a gauge arm 29 extending to the lower end of the sash and curved, as shown, to 50 allow swinging of the sash.

Below the plate 2 on the sash is a plate 7 upon the side 8 of the window casing. Said plate supports the plate 2 and the sash and has an arcuate recess to receive the end 55 4 of the plate 2 and a recess on the outer end to receive the gauge arm and limit the forward movement of the sash when closed. The lower side of plate 7 acts as a stop 9 to limit the upward movement of the rider 60 of the sash, as will be described.

The lower sash 11 is slidable in the channels 10 in the frame 8 in the usual manner. The said sash is mounted on riders 12, preferably of sheet metal construction. As 65 shown in Figs. 2 to 4, the riders are made in channel iron form. The inner wall 13 is of proper width to fit the channels 10 of the casing. The forward side 14 is closed and the side 15 adjacent the sash is of slightly greater width than the channels 10 and 70 slightly overlaps the outer side of said channels. The outer side of the rider is open at 16 to allow the sliding therein of the plates 2 and 7 of the upper sash and the 75 casing.

Each rider has a cross brace 17 therein secured by welding or otherwise to the inner and outer walls 13 and 15. Said brace has an upper shoulder 18 with an opening 19 80 therein through which a sash cord 20 may be secured. A similar lower shoulder 21 serves as a support for a rubber cushion 22 which, when the lower sash is raised, contacts with the stop member 9, as previously 85 mentioned. The body of brace 17 is extended parallel with the sides 13 and 15 between said shoulders allowing a slideway above said cushion 22 into which the plates 3 and 7 may project so as to hold the rider 90 in position when the sash is operated thereon.

The side wall 15 of the rider is extended above the body of the rider and has a slightly offset pin-receiving recess 23 therein. Said recess is somewhat elongated and has a 95 throat with a beveled lower side leading

thereto. The forward side of the throat is beveled at 25 to assist in moving the upper pin 6 upon the sash into the throat 24 and the recess 23 after it has been removed. The 5 lower end of the rider, adjacent the forward side, has a pin-receiving opening 26 therein, also slightly elongated and inclined upwardly and forwardly from the lower end and adapted to receive the lower sash pin 28. 10 It will be noted that the said pin 28 seats normally toward the rear of the rider approximately aligned with the upper pin 6 though slightly to the rear thereof.

In operating my window, it is to be understood that when the lower sash and rider are in lower closed position, the upper pin 6 projects laterally into the recess 23 and seats also in the recess 5 in the plate 2 on the upper seat, which projects into the inner channel of the rider. When the sash is raised, the pin 28 moves in the slot 26 upwardly and forwardly, thus throwing the upper pin 6 rearwardly, preventing it from accidentally moving into the throat 24 and forwardly. 25 The riders may be raised with the sash until it is in the position shown in Fig. 1. The rubber cushion 22 is then in contact with the stop arm 9. By further raising the said sash and pulling forwardly on the upper end 30 the pin 6 of the sash will be brought into the throat 24, allowing the upper end of the sash to be swung forwardly into the room, as indicated in Fig. 1. This will allow the upper end to be moved through 180° to 35 expose the outer side of the sash for cleaning. If it is desired to remove the sash entirely from the riders, the sash is swung inwardly to about horizontal position and then one side of the sash is tipped upwardly to tilt the 40 lower pin out of opening 26 and the sash may be then swung laterally in a horizontal plane and the pin freed of the rider. After one pin is freed of the rider, the other pin will easily be disengaged to allow the removal of 45 the sash. The sash may be again mounted on the rider by a reverse operation.

My construction is simple and strong and may be easily operated. It is to be noted that the placing of the lower opening 26 50 inclined upwardly and forwardly of the central axis of the rider throws the upper pin 6 rearwardly in the recess 23, so that it will ordinarily engage the hooked upper end of said recess and be thereby prevented from 55 accidental removal from the rider in operation.

Having thus described my invention, what I claim as new and desire to protect by Letters Patent is:

60 1. In a window, a casing, a lower sash, opposite riders on said sash adapted to slide in channels in said casing, said riders having upper pin-receiving recesses opening forwardly and upwardly, and lower pin-receiving 65 openings inclined to a point for-

wardly of the line of said recesses, pins on said sash engaging in said openings and recesses, and a stop arm on said casing approximately midway thereof, and means in said rider adapted to contact with said arm 70 and limit the movement of said rider in an upward direction.

2. In a window, a casing, a lower sash, opposite riders on said sash adapted to slide in channels in said casing, said riders having 75 upper pin-receiving recesses opening forwardly and upwardly, and lower pin-receiving openings, said recesses and openings being out of vertical alignment and pins on said sash engaging within said recesses and 80 openings said upper pins being thereby forced rearwardly when said sash is raised on said riders.

3. In a window, a casing, a sash, riders on opposite sides of said sash slidable in 85 channels in said casing, said riders being of channel iron construction opening outwardly of the window, cross braces in said riders, means to attach sash cords to said braces, upper and lower pins projecting into said 90 riders, and means on said casing engaging said cross braces to limit the upwardly movement of said riders in said channels.

4. In a window, a casing, a sash, riders on opposite sides of said sash slidable in 95 channels in said casing, said riders being of channel iron opening outwardly of the window, a stop plate on said casing projecting into said rider, a cushion in said rider adapted to engage said stop plate, and limit the 100 movement of said rider, and pins on said sash removably engaging said riders.

5. In a window, a casing, a sash, riders on said sash slidable in said casing, a stop plate on said casing projecting into a channel in 105 said rider, a cross brace in said rider adapted to engage said plate to limit the movement of said rider, and upper and lower pivot pins on said sash engaging in said 110 rider, said pins being arranged out of alignment, said lower pin being adapted to move forwardly to throw the upper of said pins rearwardly so as to resist the removal of said pin from said rider.

6. In a window, a casing, an upper sash, 115 a sash plate thereon having a gauge arm extending to the lower end of said sash, a forward arm on said plate having its lower side curved on the arc of a circle, and a supporting plate on said casing shaped to 120 interfit with said sash plate and permit a pivotal movement of said sash plate thereon.

7. In a window, a casing, an upper sash, a sash plate thereon having a gauge arm extending to the lower end of said sash, a forward arm on said plate having its lower side curved on the arc of a circle, a supporting plate on said casing shaped to interfit 125 with said sash plate and permit a pivotal movement of said sash plate thereon, a lower 130

sash slidable in said casing, and a stop arm on said supporting plate to limit the movement thereof.

8. In a window, a casing, having opposite channels therein, riders slidable in said channels, a window sash on said riders, said riders having pin receiving recesses at their upper ends, said recesses extending upwardly and then forwardly, there being lower pin receiving slots inclined upwardly and forwardly, pins on said sash fitting in said recesses and slots, whereby when said sash is moved upwardly said lower end will be thrown forwardly tending to hold said

upper pins in said recesses, for the purpose 15 described.

9. In a window, a casing, a sash, riders on said sash, slidable in said casing, said riders being of channel iron construction, cross braces in said riders, arranged for attachment thereto of sash cords, and means on said casing engaging said brace to limit the movement of said riders.

In testimony whereof I hereunto affix my signature this 10th day of December, A. D. 25 1926.

CLAUDE A. LEWIS.
